UNITED STATES PATENT OFFICE.

CHARLES J. KINTNER, OF NEW YORK, N. Y.

ELECTRIC RAILWAY.

SPECIFICATION forming part of Letters Patent No. 700,130, dated May 13, 1902.

Application filed December 5, 1900. Serial No. 38,724. (No model.)

To all whom it may concern:

Be it known that I, CHARLES J. KINTNER, a citizen of the United States, residing at New York, in the borough of Manhattan, county 5 and State of New York, have made a new and useful Invention in Electric Railways, of which the following is a specification.

My invention is directed particularly to improvements in that type of electric railways known in the art as "third-rail" systems, in which a current feeder or main is connected with a source of electrical energy at a power-house and extends over the entire route, sectional third rails or conductors being located in close proximity to the road-bed and provided with means for automatically connecting the same to and disconnecting them from the current feeder or main as a car, vehicle, or train travels by or thereover; and it has for its objects, first, to provide a sectional-third-rail safety system of electric railways adapted especially for use in tunnels, on elevated structures, and on suburban or cross-country roads or generally in places where 25 there is a comparatively small amount of surface traffic; second, to provide a sectional-third-rail safety system of electric railways in which rear and front end collisions are avoided by so controlling the movements of the switches between adjacent third-rail sections and the current feeder or main that when a car, vehicle, or train is passing by or over any third-rail section and utilizing current therefrom no current can be supplied to 30 any car, vehicle, or train entering the sections immediately in the front or rear thereof; third, to provide a sectional-third-rail safety system of electric railways in which rear and front end collisions are avoided by 35 so controlling the movements of the switches between adjacent third-rail sections and the current feeder or main that when a car, vehicle, or train is passing by or over any third-rail section and utilizing current therefrom no current can be supplied to 40 any car, vehicle, or train entering the sections immediately in the front or rear thereof and to combine such a system with a system of safety and danger signals; fourth, to provide a sectional-third-rail safety system of electric railways with means for avoiding front and rear 45 end collisions, said means being so arranged

that the switching mechanism for the sections immediately in the rear and front of that over which a car, vehicle, or train is passing are 55 rendered temporarily inoperative, and to combine with said means additional means between the ends of adjacent sections for enabling a motorman to cause his car or vehicle to enter upon the same section with another car or vehicle preceding and to maintain said section alive during the time that the car is passing by or thereover, even after the first-named car has passed out of or off the section by or over which it was moving; fifth, 60 to provide a sectional-third-rail safety system of electric railways with means for avoiding front and rear end collisions, said means being so arranged that the switching mechanism for the sections immediately in the 65 rear and front of that over which a car, vehicle, or train is passing are rendered temporarily inoperative, and to combine with said means additional means between the ends of adjacent sections for enabling a motorman to cause his car or vehicle to overtake a preceding car, even after it has passed off the section next in advance, and also to provide additional signaling mechanism for giving a special indication or signal to 70 the motorman of following cars or vehicles that two or more cars or vehicles are passing over a preceding section; sixth, to provide a sectional-third-rail safety system of 75 electric railways embodying a current feeder or main, a series of sectional third rails or conductors normally disconnected therefrom, and safety-circuits including releasing-circuits for rendering the switches temporarily inoperative with a series of permanent glowing or burning illuminating or lamp signals located one between each succeeding pair of third-rail sections for the purpose of indicating to a motorman either at night or in a tunnel at all times the beginning and 80 ending of successive sections of these rails; seventh, to provide a sectional-third-rail safety system of electric railways embodying a current feeder or main, a series of sectional third rails or conductors normally 85 disconnected therefrom, and safety-circuits including releasing devices for rendering the switches temporarily inoperative, with a series of permanent glowing or burning illu- 90 95 100

- minating or lamp signals located one between each succeeding pair of third-rail sections for the purpose of indicating to a motorman at night or in a tunnel at all times the 5 beginning and ending of successive sections, and to combine with the same a series of danger illuminating signals or lamps located in close proximity to the first-named lamps and controlled by the movements of the cars or 10 vehicles, so that the condition as to "safety" or "danger" may be indicated to each motorman before his car or vehicle reaches said sections in succession; eighth, to provide manual circuit-breaking switches near each of the switch-boxes of a safety third-rail system of electric 15 railways so related to the automatic switches and current connections therefor and to the current feeder or main that any one or all of said third rails may be left permanently electrically connected to the current feeder or 20 main when desired, so as to constitute, in effect, a continuous-third-rail system over any part or all of the route and for any length of time.
- 25 My invention will be fully understood by referring to the accompanying drawings and following specification, the especial points of novelty being particularly pointed out in the claims at the end thereof.
- 30 Figure 1 is a diagrammatic view illustrating in detail a complete sectional-third-rail safety system embodying a power-house generator, a current feeder or main extending therefrom over the route, a starting-switch at the 35 power-house, my novel form of rotary switches, a system of safety and danger signals, and a diagrammatic view of a car passing over one of the sections from left to right. Fig. 2 is a plan view of one of my novel mechanically-actuated switches and one of the 40 switch-boxes as applied in connection with elevated structures, tunnels, and suburban or cross-country roads, where it is not necessary to have the switches and switch-boxes located beneath or flush with the road-surface. Fig. 3 is a transverse sectional view of one 45 of the switch-boxes adapted for use in connection with the form of switch illustrated in Fig. 2, taken on the line S T, Fig. 4, and as seen looking thereat from left to right in the direction of the arrows, the spiral thread or fin of the tubular rotary switch, the switch-actuating trolley for rotating the switch, all located outside of the switch-box, and the 55 switch-circuit-controlling mechanism inside the box being all shown in elevational view. Fig. 4 is a transverse sectional view taken on the broken line Q R, Fig. 3, and as seen looking thereat from the top toward the bottom 60 of the drawing in the direction of the arrows, the end of one of the switches, its journal-bearings, the electromagnets for controlling the release of the switches, together with yielding means for maintaining the switch 65 normally in a given position, being shown in plan view, the extreme end of the switch and the downwardly-extending switch-controlling

arm within the switch-box being broken away for the purpose of better illustrating the resultant action upon the connections therein. 70 Fig. 5 is a transverse sectional view of one of the third rails, its means of support, the protecting - conduit, the current feeder or main, safety circuit-conductors, and a part of the cross-ties supporting said parts, the standards for supporting the third rails, a part of the trolley, and the interconnecting bolts of the structure being all shown in elevational view. Fig. 6 is a longitudinal sectional view taken on a broken line through Fig. 5 and as 80 seen looking thereat from right to left. Fig. 7 is a diagrammatic view, similar in many respects to Fig. 1, of the preferred form of my novel system, in which there is utilized only one electromagnet in each switch-box, a series of permanent glowing or burning illuminating or lamp signals being also shown diagrammatically for the purpose of indicating to motormen the beginning and ending of each third-rail section. Fig. 8 is a detail 90 view illustrating the means for and manner of operating any one of the switches manually whenever it becomes necessary so to do. Referring now to the drawings in detail and first to Fig. 1, *d* represents the power-house dynamo, and *c* the current feeder or main extending over the route, *t t* the tram-rails of the entire road, and *11* pairs of branch feeders running from the current feeder or main to armature-levers *17* in switch-boxes between each pair of third rails or sectional conductors *r r*, there being shown in the diagram five such sections, from section No. 1 to section No. 5, inclusive. *s s* are spring-terminals located within the switch-boxes, 105 there being one pair in each switch-box, (see also Fig. 3,) and *2 7*, *2 7* are safety-circuits connected to the opposite ends of each sectional third rail or conductor and to the spring-terminals *s s*, said safety-circuits running in opposite directions from the ends of the third rails or conductors to the distant ends of the adjacent sectional third rails or conductors, where they are connected directly to earth or to the return-circuit of the power-house generator, the arrangement being such that under normal conditions there is no electrical potential upon the sectional third rails or conductors or upon the safety-circuits. *fu fu* are fuses of well-known form, located in 110 the branches *2* of the safety-circuits between the sectional third rails or conductors and the spring-terminals *s s*. *si si* is a signal apparatus located in each of the safety-circuits *2 7* and including both visual and audible 115 signals, if need be, of any well-known form electromagnetically controlled in a manner well understood by those skilled in the art, there being two of such signals located at the entrance of each section on opposite sides of 120 the tracks and closely adjacent thereto, the operative parts thereof being supported in any well-known form of post or tower. 15 15 are releasing-electromagnets located in the

safety-circuits 27, 27 and having armature-levers 17 17 with hooks at their free ends, there being one pair of said magnets in each switch-box. These hooked armature-levers 5 17 17 and spring-terminals *s s* constitute the conducting-terminals for locking the sectional third rails or conductors electrically in connection with the current feeder or main until they are released when a car passes out 10 of a section. *f f* represent the tubular rotary switches located between the ends of each adjacent pair of third rails, said switches being preferably from thirty to fifty feet in length and provided with a spiral thread or 15 fin *g* having the desired pitch. (See Figs. 2 and 3.) This spiral thread or fin is so located with relation to a switch-actuating trolley-roller *tr*, carried beneath the car, that when the car moves in one direction it will move it (the 20 switch) one way (say to the right,) and when in the other direction the other way, (say to the left.) These rotary switches are supported at their opposite ends and intermediate points, if need be, in journal-bearings with a single 25 switch-box *n*, preferably at one end, and strong spiral springs *j j* are secured, exterior to the box, to downwardly-extending arms from the switch, the arrangement being such that a vertical arm *h*, located within the switch- 30 box, assumes normally the position shown in Fig. 3 between the ends of the two yielding or spring terminals *s s*, secured to the insulating material *i* within the box. *hv* is a hand-switch at the power-house for starting the cars over 35 the route, and *sw* is a releasing-switch for disconnecting the third-rail section nearest the power-house. 16 16 represent, diagrammatically, the wheels of a car traveling in the direction of the arrow and just entering section 40 No. 3. *mo* represents the motor on board of the car connected by a conductor 44 to the current-collecting trolley 14, which makes electrical contact with the third rails *r* as it passes thereover. The operation of this form 45 of the apparatus is as follows: For the purpose of starting a car at the power-house the starter operates the hand-switch *hv*, causing the spring-terminal *s* to be locked or held up behind the hook of the armature-lever 17 of 50 the releasing-electromagnet 15, thereby connecting the third rail *r* of section No. 1 to the current feeder or main by branch feeder 1, armature-lever 17, spring-terminal *s*, fuse *fu*, and branch conductor 2 of the safety-circuit 55 27. As the car illustrated in the drawing is just entering section No. 3 and leaving section No. 2, for the purpose of understanding the operation it will be sufficient to describe the circuit connections as operatively illustrated at that point. As it entered section 60 No. 3 the trolley-roller *tr*, bearing upon the spiral thread or fin *g* of the switch *f*, (see also Figs. 2 and 3,) caused said switch to be rotated gradually and without shock from right 65 to left or, as seen looking at Fig. 2, from the left toward the right hand end of that figure, so that the insulating-pin *p* at the lower end of the arm *h* (see Fig. 3) caused the spring-terminal *s* to be hooked up behind the hook of the armature-lever 17 of the releasing-electromagnet 15 on the right. Consequently the circuit was closed from the power-house generator *d* through the current feeder or main *c*, branch feeder 1, armature-lever 17 of magnet 15 at the entrance of section No. 3, spring-terminal *s*, fuse *fu*, branch conductor 2 of the safety-circuit 27, third rail *r* of section No. 3, current-collecting trolley 14, and conductor 4 to the motor on board of the car by the wheels 16 to earth and return, thus causing 80 the car to advance from left to right in the direction of the arrow. A branch circuit was at the same time closed from the spring-terminal *s* by the branch 7 of the safety circuit or conductor 27 to the rear, through releasing-electromagnet 15, through the magnetic signal-controlling apparatus in the box of the signal *si* to earth, thus setting the signal *si* to "danger" so long as the car remains over section No. 3 and giving both a visual and audible danger-signal at the entrance of section 85 90 No. 2 that a car is on section No. 3. It will also be noticed that inasmuch as the armature-lever 17 of electromagnet 15 at the entrance to section No. 2 is held in its forward position, as shown, no current can be available for any car entering section No. 2 from the rear so long as the car is taking current from third rail *r* of section No. 3, because even if the spring-terminal *s* be moved into its proper position by the switch *f* at the entrance to that section it will not come into electrical contact with or be locked by the hook of the armature-lever 17 of electromagnet 15, so that an incoming car will simply pass and rotate 100 the switch and stop for lack of current, said switch being inoperative for the purpose of connecting this third rail or conductor to the current feeder or main until the car has passed out of the section in advance or until 105 the switch at the end of the next section in advance has been rotated. Returning again to the spring-terminal at the entrance of section No. 3, a third circuit was closed from the third rail *r* through both branches of the 110 safety-circuit 27, running to the distant end of section No. 4, electromagnet 15 at that point, and the signal-operating apparatus in the box of signal *si*, thus displaying a visual danger-signal and operating an audible danger-signal 115 120 at that point while the car remains on section No. 3, so that an incoming car in the opposite direction will have a warning two sections in advance. It will also be apparent that said incoming car at the entrance of section No. 4 on the right will not advance after it passes and rotates its switch *f*, because the spring-terminal *s* will not be held up when the switch actuates it, the hook of the armature-lever 17 of electromagnet 15 being held in its 125 front position during the time that a car is passing by or over section No. 3. The system is therefore a complete block and safety system 130 in two senses—first, in that no current can be

utilized by cars either in front or in the rear of a car which is utilizing current from a given section; second, in that danger and safety signals, both audible and visual, are heard and displayed in the front and in the rear of a car upon a given section; third, in that all of the sectional third rails or conductors and all of the safety-circuits for controlling the operation of the switches and the signals are normally so connected to the station-generator that they are without current potential, thereby making it absolutely impossible to receive dangerous shock from the exposed conductors and avoiding any possibility of current leakage in all of the conductors which extend over the route parallel with the tram-rails, the only conductor of any substantial length having current potential being the positive-current feeder or main *c*, which is well insulated, as are also the very short branch feeders 1, which connect the current-feeders directly to the armature-levers 15.

It is obvious that the arrangement of electromagnets 15, safety circuits or conductors 2 7, signal mechanism *si*, and the several circuits and circuit connections, as shown in the diagram, admit of the possibility of running cars in either direction at will. At the extreme left of the drawings is shown a switch *sw*, the function of which is to release the spring-terminal *s* of section No. 1 when a car returns to the power-house. This releasing-switch *sw* is so located with relation to the switch-actuating trolley-roller *tr* carried by the car that when it enters the power-house the circuit will be closed through safety circuit or conductor 7 to releasing-electromagnet 15 on the extreme right of section No. 1, thus releasing the spring-terminal *s* and restoring the signal *si* between section No. 1 and section No. 2 to "safety."

Referring now to Fig. 7 of the drawings, I will describe a preferred modified form of the invention in which there is only one electromagnet 15 located in each switch-box, the magnets being preferably of the horseshoe type and so constructed that the coils thereof are connected independently to earth or the return-circuit of the power-house generator on one side and on the opposite sides one to the end of the third rail of one of the sections next adjoining and the other to one of the spring-terminals *s* at the end of the section next adjoining in the other direction and also to the adjacent end of the next sectional rail in that direction, the arrangement being such that a single armature-lever 17 in each switch-box controls the releasing of the spring-terminals *s* when the magnets are energized by one coil on either leg of the core thereof. Upon the left of this diagram I have illustrated means for enabling a motorman to cause his car or vehicle to enter upon the same section with another car or vehicle preceding it in either direction and to maintain said section alive during the time that said car is pass-

ing thereover, even after the first-named car has passed off the section, said means consisting of shunts or branch circuits of the safety circuit or conductor 2 7 around both coils of the magnet 15 and including electromagnets 31, the armature-levers of which are normally on their back stops and included normally in the circuits with the coils of the magnets 15, danger-signaling apparatus *si*, lamps 18, and switches 27, the front contacts of said armature-levers being adapted to make circuit through the magnets 31, as shown in dotted lines, and to temporarily shunt the coils of the magnets 15. 33 33 are signal-boxes for concealing visual signals 35 35, carried by the armature-levers 32 32. It will be understood, of course, that there should be one pair of these magnets 31, together with their armature-levers, shunt and other circuit connections, between each pair of third rails, only one set thereof being illustrated in order not to unnecessarily complicate the drawings, and that all of this apparatus shall be arranged in the proper signal posts or towers. This feature of my invention also contemplates the use of an additional lamp of a different color from the lamp 18 and so arranged that when the armature-lever 32 is on its front stop and the signal 35 is displayed a different-colored lamp, as a green lamp, will be exposed, such an arrangement being easily effected by a circuit-breaker between the pivoted portion of the armature-lever 32 and the multiple branch circuits running to the signaling apparatus *si* and lamp 18, so that when the armature-lever is moved up a new or independent circuit will be effected to earth through the green lamp, or these green glowing-lamps may be arranged in multiple circuit with the magnets 31 and in series with the red glowing-lamps 18, so that both sets of signals will be displayed at one and the same time, thus giving to the motorman

indication of the fact of danger at the entrance of a given section and also an especial condition of affairs in that two or more cars are grouped or bunched in a preceding section, as indicated by the green light. 27 27 are hand-switches in the safety-circuits or conductors 2 7 and between all of the signaling apparatus included in these circuits and the earth, their function being to enable one to operatively disconnect the safety-circuits of any or all of the third rails or sections, so as to leave the latter permanently connected to the current feeder or main *c*.

I have also illustrated in Fig. 7 of the drawings a separate current feeder or main extending over the route and operatively connected with an independent generator *g'* at the power-house station, said feeder or main including in circuit a series of electric lamps 1, one of said lamps being located in the signal post or tower between each pair of third rails or sections, the arrangement being such that said lamps will indicate continuously at night and in tunnels at all times the location of the signal-posts between the several

third rails or sections of the entire system. I have also shown incandescent lamps 18 18 at the signal-posts, the globes of which are preferably red for indicating "danger," and said 5 lamps are located in reasonably close proximity to the permanent lamps 1, the latter being preferably series arc-lamps.

In Fig. 8 I have illustrated portable means for and the manner of manually operating 10 any one of the switches *f* in the event of its becoming necessary so to do, said means consisting of a lever 28, provided with an insulating handle 29 and hook 30, the manner of rotating the switch being made apparent on 15 inspection of this figure of the drawings, it being obvious that the motorman has simply to apply the device, as shown, with a hook 30, taking behind one side of the thread or fin *g*, and exercising the necessary pressure upon 20 the handle 29 until the spring-terminal *s* is locked behind the armature-lever 17 by the action of the pin *p* at the lower end of the arm *h* in the corresponding switch-box. Each motorman would of course be provided with one 25 of these manual switch-operating devices. As the general diagrammatic arrangement of this modified form of the invention is very similar to the system illustrated in Fig. 1, a description of the mode of operation will be 30 at once obvious. The car has just entered the left-hand end of section No. 3 and the trolley-roller *tr* has just rotated the rotary switch *f* so that the crank-pin *p* on the shaft thereof at one end in the switch-box has forced 35 the spring-terminal on the right into the position shown, the armature-lever 17 locking it. Consequently the circuit is closed from the dynamo *d* by the current feeder or main *c* to branch feeder 1, armature-lever 17, spring terminal *s*, safety circuit or conductor 2 7 to the 40 rear, through the right-hand coil of the releasing-electromagnet 15, between section No. 1 and section No. 2, by safety circuit or conductor 2 7, semaphore signaling apparatus *si*, incandescent lamp 18, and switch 27 to earth, thus 45 indicating danger at the entrance of section No. 2 and also placing the armature lever 17 of that magnet in its upper position, so that should a car enter from the left upon section 50 No. 2 no current will be supplied thereto. In the same manner, tracing the circuit through branch conductor 2 of the safety circuit 2 7 to the third rail *r*, the third rail is made alive and the trolley 14 conveys the current through 55 conductor 4 to the motor and by the wheel 16 of the car to the tram-rails *t* and to earth. A third branch circuit was also closed through the sectional third rail *r*, as was the case in the system illustrated in Fig. 1, to the distant 60 end of section No. 4 by safety circuit or conductor 2 7 through the left-hand coil of the releasing-electromagnet 15, through the semaphore signaling apparatus *si*, incandescent lamp 18, and switch 27 to earth, indicating "danger," at the entrance of section No. 65 4 on the extreme right. As the armature lever 17 is held up by releasing-electromagnet

15 at that point, no current will be supplied to a car entering at the right-hand end of section No. 4.

By arranging the series of lamps 1 one at each signal-post in the feeder or main *a* in circuit with an independent generator *g* the motormen have a visual indication at all times, at night or in the dark, of the beginning and ending of each third rail or sectional conductor, and as a car or train travels over the route when it approaches any one of these lamps if no red light be indicated in the companion lamp 18 the motorman is at 75 liberty to pass on with his car into the next section. If it be desirable or necessary to run cars upon adjacent sections of any part of the system, it is only required that a motorman approaching a given section where a danger-signal is displayed shall manually move the armature-lever 32 from its back contact-stop into contact with its front contact-stop, thereby closing the circuit, as illustrated in dotted lines, from the third rail *r* of section No. 3 80 by safety circuit or conductor 2 7 and shunt through magnet 34, armature 32, and the signaling mechanism through switch 27 to earth, thus shunting the coils of the magnet 15 between sections No. 1 and No. 2 and allowing the armature 17 to be returned to normal position as long as the car in question 85 remains upon section No. 2. At the same time a special signal 35 is displayed for day use and a special or green lamp for night use, 90 thus displaying at that station at any one time—say in the night under these conditions—a white light, a red light, and a green light. When, however, it passes into section No. 3, the armature-lever 32 is released and 95 restores the circuit through the coils of the magnet 15, leaving the conditions as before, with only a red-light danger-signal displayed or a semaphore in day-time. In the meantime if the car which has just passed section No. 100 2 had been speeded up sufficiently it would reach section No. 3 and overtake the car in advance before it had left that section, so that both cars might travel together. In like manner any number of cars might be congregated upon any section.

The most essential feature of novelty in the system illustrated in Fig. 7 lies in utilizing the individual coils of the single releasing-electromagnet 15 in each switch-box to operate the armature-lever 17 for cars moving in either direction, so that there is no possibility of leaving any sectional third rail *r*, connected to the current feeder or main, no matter in which direction a car may be traveling. As 110 it is apparent that should the car which is now moving from left to right over section No. 3 return in an opposite direction after it has passed the switch, the trolley-roller *tr* would rotate the switch *f* in a reverse direction and connect the spring-terminal *s* on the left with the armature-lever 17, so that both terminals would be connected. As soon, however, as the car running backward reaches

section No. 1 on the left the releasing-electro-magnet 15 will be energized, and consequently the armature-lever 17 will release both of the spring-terminals *s s*.

5 Referring now to Figs. 5 and 6 of the drawings, I will describe the means whereby I afford additional protection to the current-feeder, safety-conductors, and third-rails and also the manner in which I support said 10 third-rails in the middle of the road-bed so as to obtain the best insulating effects and also avoid any possibility of damaging shocks to persons or animals should they cross the roadway during the time that any section is 15 alive, my invention contemplating, particularly in cross-country roads, the use of long third-rail sections in places where there is little travel and shorter sections in places where the travel is more general. *b* represents 20 one of the cross-ties, in the middle of which, between the tram-rails, are secured at intervals metal standards 22, provided with sufficient base-support to give them stability, said standards being screwed into the ties, as 25 shown, and provided at their upper ends with rectangular-shaped extensions 25, having bolt-holes near their opposite ends, the entire standard above the cross-tie being preferably subjected to any of the well-known vitrefying 30 processes for giving better insulating effects. *e* represents the longitudinal supporting-rails, made preferably of treated wood, so as to obtain the best insulating effects, and provided on their under sides with short rectangular-shaped 35 grooves adapted to fit snugly over the rectangular-shaped extensions 25 of the standards or supports 22, said rails being V-shaped on their upper surface and adapted to sustain the third rails *r*, made preferably 40 of copper or phosphor-bronze, and correspondingly V-shaped with their lower edges of knife-like nature, so as to readily convey away by drip any moisture which accumulates thereon. The standards 22 are secured at 45 proper distances—say from six to eight feet—as the location of the ties may warrant, and the parts are all secured together by bolts 24 and nuts 23, said bolts being insulated from the extensions 25 of the standards 22 by short 50 tubes of insulating material, as shown. 14 represents a grooved trolley-wheel resting upon the third rail *r*. Upon each side and adjacent to the base of the standards 22, I secure a conduit made up of protecting-timbers 55 19 19, having overhanging ledges or covers 20 20, all of said parts being held together and to the ties by screw-bolts 21 21 and in such manner that a narrow groove is located 60 above the third rails, through which the trolley-wheel 14 passes, the arrangement being such that should a person or animal pass over the roadway there is no danger of a damaging shock and also such that rain or snow will pass down through the slot and out between the cross-ties *b*. In the construction 65 of this conduit grooves *i* and *j* are cut in the upper faces of the timbers 19, so as to con-

stitute casements or inclosures for the current feeder or main *c* and safety-circuit or other conductors, the overhanging ledges 20 70 acting as covers therefor. These casements *i* and *j* may, if preferred, be cut in the lateral or outside faces of the timbers 19 and covered with weather-strips let into the faces thereof and secured by screws or otherwise, 75 so that the wires may be removed or repaired without removing the covers or overhanging ledges 20, or there may be any number of such grooves in the lateral outside faces of the timbers 19 for holding independently the 80 different types or classes of conductors to be used in connection with the system, all of said grooves being covered by a single flat strip of the height of the timbers 19. With such an arrangement I am enabled to fully 85 protect all of the electrical conductors of the system, including the sectional third rails, in such manner as to make the structure absolutely safe and also insure the best insulation and protection for the entire system of conductors. 90

I do not limit myself to the particular details of construction hereinbefore described, and illustrated in the accompanying drawings, for accomplishing the several results or 95 objects for which the invention is designed, as many of the features thereof may be materially departed from and still come within the scope of my claims hereinafter made. To illustrate, any preferred form of mechanically-actuated switch adapted to be controlled in its action by the movement of the car may be substituted for the preferred form 100 of mechanically-actuated switch herein shown and described, such mechanically-actuated switches controlled by the movements of cars being well known in the art. I believe it is broadly new with me to combine a current feeder or main and a series of sectional third rails or conductors, which are normally electrically disconnected therefrom, with circuit-connecting devices in the nature of mechanically-actuated switches controlled by the 105 movements of a car as it passes by or over the same, together with safety-circuits and releasing devices included therein, and so arranged that when a car is passing by or over a given section the switching mechanism located at the distant end of any adjacent section is rendered inoperative until the car 110 passes out of said section, the arrangement being such that all of the working conductors extending over the route except the current feeder or main are normally without current potential, and my claims are generic 115 as to these features, it being understood, however, that the switching devices which connect the sectional conductors to the current feeder or main are mechanically controlled. Generic claims to these features without relation to the peculiar nature of the operating-switches are made in another application 120 filed by me in the United States Patent Office on the 6th day of May, 1901, bearing Serial 125

No. 58,923, and allowed October 14, 1901, the more generic claims hereinafter with relation to the sectional systems and switching devices therefor being limited to mechanically-actuated switches, nor do I make any claim in the present application to a safety sectional system of electric railways embodying a current feeder or main and a series of sectional conductors normally disconnected therefrom, together with safety-circuits, normally without current potential and embodying the features just referred to in the last clause preceding when combined with signaling apparatus, as these generic features are embodied in a separate application bearing Serial No. 76,564, filed September 25, 1901, in which application, however, the means for effecting the locked relation between the sectional conductors and the current feeder or main and for releasing the same when a car or vehicle passes out of a section are controlled by electromagnets. I wish it distinctly understood that the claims in that application, in so far as these features are concerned, are directed to the application of the generic idea without relation to any especial type of means for effecting such connection and disconnection, while in the present application I have distinctly limited the claims, in so far as these especial features are concerned, to "mechanically-controlled switching mechanism"—that is to say, switching mechanism which is actuated mechanically by the movement of a car as it passes over the route, as hereinbefore described, as illustrated in the accompanying drawings, and as particularly pointed out in the claims at the end of the specification; nor do I make any claim hereinafter to any method of operation applicable to the apparatus herein disclosed, as the method claims based upon such apparatus as is disclosed in all of the above-named applications are made the subject-matter of a still further application, bearing Serial No. 84,322 and filed December 2, 1901; nor is any claim made herein to an electric-railway switch journaled with its axis of rotation substantially parallel with the track-rails and provided with means for adapting it to be rotated gradually and continuously about its axis of rotation as a car passes over or by it; nor to a rotary switch having its axis of rotation substantially parallel with the track-rails and provided with a spiral thread or groove in the direction of its length, adapted to give the switch gradual and continuous rotation as a car passes by or over it, as these features are claimed by me in another application, bearing Serial No. 34,765, filed in the United States Patent Office on the 29th day of October, 1900, allowed December 29, 1900, forfeited and again renewed by me on the 28th of February, 1902, said renewed application bearing Serial No. 96,128.

Having thus described my invention, what I claim, and desire to secure by Letters Patent of the United States, is—

1. A safety system of electric railways embracing a current feeder or main, a series of sectional third rails or conductors normally disconnected therefrom and mechanically-actuated switching mechanism for connecting said sectional conductors to the current feeder or main as a car or vehicle passes by or over the same; in combination with safety-circuits including devices for releasing the conducting-terminals of the switches, said safety-circuits being so connected to the power-house generator as to be normally without electrical current potential, and the entire arrangement being such that when a car is passing by or over a given sectional third rail or conductor the switch at the distant end of the sectional third rail or conductor immediately in the rear thereof is rendered temporarily inoperative until the car passes out of said section, substantially as described. 75

2. A safety system of electric railways embracing a current feeder or main, a series of sectional third rails or conductors normally disconnected therefrom and mechanically-actuated switching mechanism for connecting said sectional conductors to the current feeder or main as a car or vehicle passes by or over the same; in combination with safety-circuits, two for each sectional third rail or conductor, said safety-circuits including devices for releasing the conducting-terminals of the switches and so connected to the power-house generator as to be normally without electrical current potential, the entire arrangement being such that when a car is passing by or over a given sectional third rail or conductor the switches at the distant ends of the two adjacent sectional third rails or conductors are both rendered temporarily inoperative until the car passes out of the section over which it is traveling, substantially as described. 90

3. A safety system of electric railways embracing a current feeder or main, a series of sectional third rails or conductors normally disconnected therefrom and mechanically-actuated switching mechanism for connecting said sectional conductors to the current feeder or main as a car or vehicle passes by or over the same; in combination with safety-circuits including devices for releasing the conducting-terminals of the switches and signaling devices; said safety-circuits being so connected to the power-house generator as to be normally without electrical current potential, the entire arrangement being such that when a car is passing by or over a given sectional third rail or conductor the switch at the distant end of the sectional third rail or conductor immediately in the rear is rendered temporarily inoperative and a danger-signal is displayed, until the car passes out of said section, substantially as described. 110

4. A safety system of electric railways embracing a current feeder or main, a series of sectional third rails or conductors normally disconnected therefrom and mechanically-actuated switching mechanism for connecting

said sectional conductors to the current feeder or main as a car or vehicle passes by or over the same; in combination with safety-circuits, two for each sectional third rail or conductor, said safety-circuits including devices for releasing the conducting-terminals of the switches and signaling devices, and so connected to the power-house generator as to be normally without electrical current potential, 5 the entire arrangement being such that when a car is passing by or over a given sectional third rail or conductor the switches at the distant ends of the sectional third rails or conductors immediately in the front and in 10 the rear are rendered temporarily inoperative and danger-signals are displayed until the car passes out of said section, substantially as described.

5. A safety system of electric railways embracing a current feeder or main, a series of 20 sectional third rails or conductors normally disconnected therefrom and mechanically-actuated switching mechanism for connecting said sectional conductors to the current feeder 25 or main as a car or vehicle passes by or over the same; in combination with safety-circuits including devices for releasing the conducting-terminals of the switches, said safety-circuits being so connected to the power-house 30 generator as to be normally without electrical current potential; together with additional means included in branches of the safety-circuits for enabling a motorman to cause his car or vehicle to enter upon a section 35 adjacent to a preceding section over which a car is then passing, substantially as described.

6. A safety system of electric railways embracing a current feeder or main, a series of 40 sectional third rails or conductors normally disconnected therefrom and switching mechanism for connecting said sectional conductors to the current feeder or main as a car or vehicle passes by or over the same; in combination with safety-circuits including devices for releasing the conducting-terminals of the switches said safety-circuits being so connected to the power-house generator as to be normally without electrical current potential; together with additional means for enabling a motorman to cause his car or vehicle to enter upon a section where a danger-signal is displayed, and additional signaling mechanism for giving a special indication or 55 signal to the motormen of following cars that two or more cars are passing over adjacent preceding sections, substantially as described.

7. A safety system of electric railways embracing a current feeder or main, a series of 60 sectional third rails or conductors normally disconnected therefrom and switching mechanism for connecting said sectional conductors to the current feeder or main as a car or vehicle passes by or over the same; in combination with safety-circuits including devices for releasing the conducting-terminals

of the switches, said safety-circuits being so connected to the power-house generator as to be normally without electrical current potential; together with a series of permanent 70 glowing or burning illuminating lamps or signals located one between each succeeding pair of third-rail sections, the entire arrangement being such that when a car is passing by or over a given sectional third rail or conductor the switch at the distant end of the sectional third rail or conductor immediately in the rear thereof is rendered temporarily inoperative until the car passes out of said section, and the motorman given a positive 80 indication at all times of the beginning and ending of the third rails or conductors of the system, substantially as described.

8. A safety system of electric railways embracing a current feeder or main, a series of 85 sectional third rails or conductors normally disconnected therefrom and switching mechanism for connecting said sectional conductors to the current feeder or main as a car or vehicle passes by or over the same; in combination with safety-circuits including devices for releasing the conducting-terminals of the switches and signaling devices; said safety-circuits being so connected to the power-house generator as to be normally without electrical current potential; together with a series of permanent glowing or burning illuminating lamps or signals located one between each succeeding pair of third-rail sections, the entire arrangement being such that 90 when a car is passing by or over a given sectional third rail or conductor the switch at the distant end of the sectional third rail or conductor immediately in the rear thereof is rendered temporarily inoperative until the car passes out of said section, danger-signals displayed, and the motorman given a positive 95 indication at all times of the beginning and ending of the third rails or conductors of the system, substantially as described.

9. A safety system of electric railways embracing a current feeder or main, a series of sectional third rails or conductors normally disconnected therefrom and switching mechanism for connecting said sectional conductors to the current feeder or main as a car or vehicle passes by or over the same; in combination with safety-circuits including devices for releasing the conducting-terminals of the switches, said safety-circuits being so connected to the power-house generator as to be normally without electrical current potential; together with manual circuit-breaking switches, one in each safety-circuit, the entire arrangement being such that when a car is passing by or over a given sectional third rail or conductor the switch at the distant end of the sectional third rail or conductor immediately in the rear thereof is rendered temporarily inoperative; or, any or all of the safety-circuits may be permanently interrupted in such manner that when the sectional

third rails or conductors are connected to the current feeder or main they will remain thus connected, substantially as described.

10. A safety system of electric railways embracing a current feeder or main and a series of sectional third rails or conductors normally disconnected therefrom; in combination with mechanically-actuated switching mechanism for connecting said sectional third rails or conductors to the current feeder or main and disconnecting them therefrom; together with a series of danger-signals connected permanently in circuit with the sectional third rails or conductors, the arrangement being such that the circuits including the danger-signals are normally without electrical current potential and that if a sectional third rail or conductor be left connected with the current feeder or main after a car has passed from over the same said signals will be continuously displayed, substantially as described.

11. A safety system of electric railways embracing a current feeder or main, a series of sectional third rails or conductors normally disconnected therefrom and mechanically-actuated switching mechanism having conducting-terminals for connecting said sectional conductors to the current feeder or main as a car or vehicle passes by or over the same; in combination with releasing-electromagnets for the conducting-terminals of the switches, the individual coils of said releasing-magnets being included in circuit with safety-circuits running in opposite directions and connected to earth and to the adjacent ends of distant sectional third rails or conductors, substantially as described.

12. A safety system of electric railways embracing a current feeder or main, a series of sectional third rails or conductors normally

disconnected therefrom and mechanically-actuated switching mechanism for connecting said sectional conductors to and disconnecting them from the current feeder or main as a car or vehicle passes by or over the same; in combination with a series of safety-circuits, two for each sectional third rail or conductor, said circuits being connected directly to the opposite ends of said conductors and extending to the opposite ends of the sectional third rails or conductors in the front and rear thereof; together with signaling devices included in said safety-circuits, the arrangement being such that normally there is no electrical current potential in the signaling-circuits and that should any sectional third rail or conductor be left permanently connected with the current feeder or main, said signaling devices will be continuously displayed, substantially as described.

13. In an electric-railway system a current feeder or main, sectional third rails or conductors normally disconnected therefrom; mechanically-actuated switching mechanism for connecting said sectional conductors to the current-feeder and releasing-electromagnets for disconnecting them therefrom; said releasing-electromagnets being included in circuits connected at one end directly to the sectional conductors and extending in opposite directions to the distant ends of adjacent sectional conductors where they are connected to the return-circuit of the power-house generator, substantially as described.

In testimony whereof I have signed my name to this specification in the presence of two subscribing witnesses.

CHARLES J. KINTNER.
